(No Model.)

D. S. AMSTUTZ.

PORTABLE APPARATUS FOR SCALDING HOGS.

No. 392,773.

Patented Nov. 13, 1888.

UNITED STATES PATENT OFFICE.

DANIEL S. AMSTUTZ, OF ORRVILLE, OHIO.

PORTABLE APPARATUS FOR SCALDING HOGS.

SPECIFICATION forming part of Letters Patent No. 392,773, dated November 13, 1888.

Application filed March 7, 1888. Serial No. 266,403. (No model.)

To all whom it may concern:

Be it known that I, DANIEL S. AMSTUTZ, of Orrville, in the county of Wayne and State of Ohio, have invented certain new and useful Improvements in Portable Apparatus for Scalding Hogs; and I do hereby declare the following to be a full, clear, and exact description of the invention, such as will enable others skilled in the art to which it pertains to make and use of the same.

My invention relates to improvements in portable apparatus for scalding hogs, in which a suitable frame-work supports a metal scalding-vat, with burner or fire-box, as the case may be, located underneath such scalding-vat for heating the same. A double windlass with chains is provided for raising, lowering, and turning the hogs in the vat, the one member of the windlass having a clutch, by disconnecting which the other member of the windlass may be turned to lower the hogs into the vat or to raise the hogs out of the vat; also, a grating is provided for gaging the depth to which the hogs are lowered in the vat and keep them from coming in contact with the vat-plate, so as to avoid "setting" or burning the bristles, leaving a suitable depth below the grating for the accumulation of sediment.

My invention also relates to details of construction hereinafter described and claimed.

In the accompanying drawings, Figure 1 is a side elevation, portions being broken away to show the construction. Fig. 2 is an end elevation in transverse section.

A represents a suitable supporting-frame, preferably of metal tubing, arranged substantially as shown. Fastened to the top rail, A', of the frame is a sheet-metal scalding-vat, B, preferably with rounded bottom, as shown in Fig. 2. A metal casing, C, is fastened to the supporting-frame outside the vat, and joins the latter at the top. This casing incloses a heating-chamber, C', underneath the vat, and grate-bar (not shown) may be arranged at the bottom of the casing for a wood or coal fire; but, preferably, vapor-burners c are provided, as shown, directly under the central line of the vat, these burners being connected by feed-pipe c' with gasoline-container C'', together with the necessary valves and mechanism, sub-

stantially as with vapor-burners heretofore used.

Tank B is made long enough to admit of dividing it into two compartments, B' and B'', by means of partition b, the smaller compartment, 55 B', being utilized for keeping a quantity of clean hot water on hand, while compartment B'' is used for scalding purposes. The tank is considerably deeper than is necessary for immersing the hogs, and a removable grating, b', 60 is suspended in compartment B'', this grating being supported by hooks b'', substantially as shown. This grating prevents the hog from being lowered too deep into the vat, and by means thereof the bristles and dirt that necessarily accumulate in the vat may gravitate to the bottom, and are not stirred up in manipulating the hog in the vat, thereby leaving the water above the grating comparatively clear. Both compartments are provided with the necessary discharge-pipe and valve B'. On either side and directly over the respective edges of the vat are located rollers D and E, arranged parallel with each other and extending lengthwise of the vat, these rollers being journaled in 75 suitable boxes, a, connected with the supporting-frame. Roller D is located near the upper edge of the tank, while roller E is considerably higher. Roller E has a crank, E', and sprocket-wheel e, the latter being rigidly secured to this 80 roller. Roller D has a sprocket-wheel, D', journaled on the roller, the hub of the sprocket-wheel at one end thereof having notches d, that by engaging a pin, d', that extends laterally through the roller, causes the roller and 85 sprocket-wheel to turn together. A spiral spring, F, is coiled around this roller and abuts the sprocket-wheel on the side thereof opposite such clutch. A lever, G, is pivoted at g to the frame-work, the long end of the lever serving as a handle and the short end of the lever bearing against the sprocket-wheel D' on the clutch side thereof. By means of this lever the sprocket-wheel may be moved endwise of the roller against the action of the 90 spring to disengage the notches d from the pin d', and while the sprocket-wheel is held in this position it may be revolved without turning roller D, on which it is mounted. An endless chain, H, connects the two sprocket-wheels, 95 100

and when the clutch is in mesh the two rollers, by means of the crank, are moved in unison; or by disconnecting the clutch the roller E may be turned, leaving roller D stationary. 5 Chains I, usually three in number, are permanently attached to roller E, and detachably secured, usually by means of hooks, to roller D. These chains are of such length as to admit of lowering the hog upon the grating, still 10 leaving the chains wound once or twice around each roller. In operating the device the hog is suspended over the vat by means of a derrick or other suitable device, and while in such position at least two of the chains are passed 15 under the hog, and the chains are fastened to roller D, and the clutch is thrown out of gear and the slack of the chain is wound upon roller E. The hog is then lowered upon the chains, and while the clutch is still out of gear, roller 20 E, by means of a crank, is turned in the direction to unwind the chains and thus lower the hog into the vat. After the hog is submerged the clutch is thrown into gear and the rollers are turned in the direction to still further 25 unwind the chains from roller E and wind them upon roller D, by which arrangement the hog is rolled over in the vat. The rollers may then be reversed, turning the hog in the opposite direction, and at the end of the scalding 30 process the chains should be in position, unwound from roller D. The clutch is again thrown out of gear, and the rotation of roller E is continued to wind up the chain and elevate the hog from the vat. When the chains 35 are drawn taut, the hog will roll down the chains and be discharged onto a table that is supposed to be located on the side of the apparatus next roller D. This completes the scalding apparatus, and when the chains are 40 slackened off a trifle from roller E they are in position for again receiving a hog for scalding.

What I claim is—

1. The combination, with a scalding-vat, of rollers located at the respective sides of the vat and at different elevations, chains connecting 45 with the two rollers, and mechanism, substantially as indicated, for revolving the two rollers in unison and for revolving the top roller while the lower roller remains stationary, substantially as set forth. 50

2. The combination, with a scalding-vat, of rollers mounted on the respective sides of the vat, chains extending from one roller to the other, sprocket-wheels mounted on the respective rollers and connected by an endless 55 chain, and a clutch for rendering one roller operative or inoperative, substantially as set forth.

3. The combination, with a scalding-vat and rollers located at different elevations, of chains 60 extending from the rollers in position to enter the vat, substantially as set forth.

4. The combination, with a scalding-vat and rollers located at different elevations, of chains extending from the rollers over the vat, and 65 clutch mechanism for locking one of said rollers, substantially as set forth.

5. The combination, with a scalding-vat, a grating located therein, a heating-chamber beneath the vat, and rollers, one above the other 70 and over the sides of the vat, of chains extending from said rollers, gearing connecting the rollers, and clutch mechanism for locking one roller, substantially as set forth.

In testimony whereof I sign this specification, in the presence of two witnesses, this 21st day of February, 1888. 75

DANIEL S. AMSTUTZ.
